UNITED STATES PATENT OFFICE.

FERDINAND GUY GASCHE, OF CHICAGO, ILLINOIS.

APPARATUS FOR THE CONCENTRATION OF ORES.

1,359,497.

Specification of Letters Patent. Patented Nov. 23, 1920.

Original application filed March 5, 1918, Serial No. 220,427. Divided and this application filed June 20, 1919. Serial No. 305,480.

To all whom it may concern:

Be it known that I, FERDINAND G. GASCHE, a citizen of the United States, and a resident of Chicago, county of Cook, and State of Illinois, have invented certain new and useful Improvements in Apparatus for the Concentration of Ores, of which the following is a specification.

My invention relates to apparatus for the treatment of ore to effectuate the separation of the metal particles and metal-bearing portions from the lighter gangue which comprises the greater bulk of the ore.

This application is a division of my application entitled, "Improvements in and for the concentration of ores", filed March 5, 1918, Serial Number 220,427.

It is customary to ship ores direct from the mines to large concentrators, smelters, or cyanid extractors, where the values are recovered and either purchased or returned to the miner. The initial cost and the operating expenses of such plants, and the low efficiency thereof when operated on a small scale, practically preclude any other method of ore disposal. Furthermore, the present cost of concentrating ore and recovering the values therefrom, makes it unprofitable to handle and ship any other than comparatively rich ores, with the result that low-grade ore remains unmined or if mined is treated as waste and left upon the dump at the mine; and also, rich ore deposits remain unworked because too far distant from a smelter or extractor, or for lack of transportation facilities.

The object of my invention is to overcome these difficulties by enabling men of little skill as metallurgists, and with little labor, to handle both high and low-grade ores and speedily, efficiently and economically concentrate the valuable parts thereof, in the immediate vicinity of the mine or dump; and where with little added expense the concentrates may be refined, or because of the reduction in bulk may be profitably shipped even to distant points for that purpose.

My invention comprises a novel concentrating apparatus hereinafter described and particularly pointed out in the claims:

The invention will be readily understood on reference to the accompanying drawings which form part of this specification and in which: Figure 1 is a diagrammatic

elevation of a concentrating plant embodying my invention;—Fig. 2 is a sectional detail of one of the air guns which I employ;—Fig. 3 is a view of the nozzle on the parting line X—X, viewed in the direction 60 of the arrow A;—and, Fig. 4 is a like view of the direction of the arrow B.

It should be understood at the outset that these drawings depict only the best apparatus which I have thus far devised, containing various novel features and combinations, but are not intended to imply that my invention is restricted thereto except where so limited in the claims.

Fig. 1 illustrates a mill and power house, 2, near which is the concentrating floor, 3, covered by a long shed, 4. The house, 2, contains a suitably driven conveyer, 5, for feeding ore to the mill or pulverizer, 6. The latter is driven by an engine or motor, 7. The pulverized product leaves the mill through a swinging spout, 8, adapted to deliver the pulverized ore first to one and then to another of the tanks, 9. These tanks are closed at the top by means of hopper valves, 10. The bottom of each tank is in the form of a hopper and leading therefrom is a down-spout, 11, which delivers into a mixing head, 12. This head, as hereinafter explained, contains devices for discharging 85 the pulverized ore from the tanks into respective mixing chambers, 13. Each of these mixing chambers has an elbow, 14, which communicates with the gun or nozzle, 15, the details of which, in the preferred 90 form, will be explained hereinafter. The house, 2, also contains an air compressing or blowing engine, preferably a turbo-blower, 16, of a two-stage delivery type. The outlet pipe, 17, thereof is connected to 95 the system at points within the tanks, 9, as indicated at 22 and 22' in Fig. 1, within the heads, 12, and preferably also within the nozzle, 15, as better explained hereinafter. It will be understood that the two heads, 12, 100 and their elbows preferably join a single gun or nozzle 15; that is, the plurality of tanks or reservoirs comprise means for continuously feeding the crushed ore to the gun, 15.

The gun, 15, extends through the wall, 4', of the shed, 4, and preferably is positioned to discharge the ore horizontally across the concentrating floor, 3. Obviously the gun may be aimed up or down from the hori- 105 110

horizontal and thus is a change sometimes made for the purpose of compensating variations in the quality of the pulverized ore.

The floor, 3, may be a simple flat surface, 5 but preferably is provided a plurality of ore-receiving sections or hoppers. Thus may be distinguished, the hoppers 18, 19 and 20. The hoppers, 18 and 19, are preferably equipped with outlet conduits or tunnels, 18', 10 and 19', respectively. The hopper, 20, may have one or more outlets, but as a rule none is required as it is upon this section that the rich concentrate is deposited and only a periodic clearing of that portion of the floor 15 is required. Any suitable means may be employed for clearing the conduits or tunnels, 18', 19'. The hopper 19 receives the poor concentrate, and my invention comprehends the return of the poor or low grade 20 concentrate from the hopper, 19, to the mill to be reground and again discharged through the gun, 15. The shed has a closed far end, 4", which is preferably inclined, as shown. The roof of the shed, or, if desired, the floor 25 thereof, contains pressure relief openings, 21, and save for the necessary doors and windows, these may be the only openings in the walls of the shed.

Referring now to Figs. 2, 3, and 4, for the 30 details of the preferred form of my novel gun or nozzle, the parts before referred to may be identified as follows, to wit: The tank, 9, the down-spout, 11; the head, 12; the elbow, 14; the gun or nozzle, 15; and the 35 blower pipe, 17. One branch, 17', of the pipe, 17, communicates with the pipes, 22 and 23, containing respective valves 22' and 23'. The pipe, 22, leads through the side of the tank, 9, and is bent downwardly 40 so that it substantially enters the down-spout, 11. At the lower end of the down-spout is a casting, 12', which contains in its central bore a tube, 24, having at its lower end a valve seat, 25, and also a conical surface, 26. A valve, 27, co-acts with the seat, 25, to regulate the flow of ore from the tank. This valve is carried by a stem, 28, having a hand wheel, 29, on the exterior of the elbow portion, 13, 14. The upper part of the part 45 13 contains an enlarged cavity, 30, which is continued in the cavity, 31, of the intermediate casting or member, 12", of the head. This intermediate part contains an adjustable conical ring, 32, which is movable 50 toward and from the cone, 26, to provide the conical air passage, 33. Within the part, 12", is an annular cavity, 34, which communicates with the pipe, 23, and hence with the conical passage, 33. A combining tube, 35, 55 presents its large end to the lower end of the elbow, 14. The small end of the combining tube, 35, delivers into the pipe, 36, one section, 36', of which preferably is flexible. To the forward end of the pipe, 36, I connect a 60 second combining tube, 37, the tip of which is

formed by a nozzle, 38. Attached to the part, 37, is a head, 39, which contains a central cavity, 40, and also an annular cavity, 41. The second branch, 17", of the blower pipe, 17, communicates with the cavity, 41. 70 A face plate, 42, closes the end of the head, 39, leaving, however, a narrow annular crack or opening, 43, whereby communication is established between the cavity, 41, and the cavity, 40. A threaded opening, 43', contains a nozzle plug, 44, which has a specially formed conical bore, 45, which is in exact axial alinement with the tip, 38, and the tube, 37. Attention is called to the slight enlargement or flare, 45', at the inner end of 80 the bore, 45. A bridge arm, 42', that is integral with the plate, 43, contains a central bore, 42", which holds the nozzle, 38, in axial alinement with the tube, 37, and in firm abutment with the end thereof. I have 85 thought it unnecessary to refer in detail to the several bolts and flanges whereby the several members are joined. The forms, dimensions, and relations of the parts, 37, 38, 45 and 45', will be explained in the course 90 of the description of the operation of the apparatus depicted.

The operation is as follows: By means of a suitable mill, 6, the ore as it comes from the mine or dump is pulverized, granulated 95 or powdered with substantial uniformity. The degree to which pulverization should be carried is determined by the character of the ore, but in many cases it is sufficient if the pulverized ore is fine enough to pass through a twenty-mesh screen; and in practically all cases a pulverization corresponding to a forty-mesh screen will prove sufficient. Finer pulverization ordinarily is too slow 105 and too expensive and also makes a slower precipitation of the ore. Obviously, part of the ore will be reduced to a still finer state, leaving the larger particles of the maximum sizes indicated.

Compressed air from the blower 17, flows 110 through the nozzle or gun, 15. The pulverized ore which is furnished by the mill is fed into this stream of air and taking on approximately the velocity of the stream of air is thus ejected or discharged from the 115 gun, 15. In practice a substantially uniform velocity is imparted to every particle of the ore, and all of the particles leave the mouth of the gun or nozzle, 15, at a substantially uniform and very high velocity. 120 The velocity thus imparted would afford each particle of the ore a maximum trajectory of many times the length of the shed, 4, were it not for the force of gravity and the baffling or interfering effect of the air 125 or atmosphere in the shed. Due to such impedance, the lighter particles of gangue are caused quickly to lose velocity and to settle upon the concentrating floor at points not far remote from the mouth of the gun, 130

15. Particles of metal, on the other hand, being heavier, for a longer time resist the impeding action of the air and carry nearly or quite to the end of the shed before settling upon the floor. Other particles of gangue which are burdened with small particles or quantities of metal fall upon the floor at an intermediate point. The high velocity which I impart to the particles by 5 means of the air jet or blast, is not so much for the purpose of throwing the particles to great distances beyond the mouth of the gun as for the purpose of accentuating the reaction of the air in the shed against the 10 particles, whereby I secure a clear and distinct separation of the particles according to respective masses and shapes, and enable even a very slightly burdened particle of gangue to penetrate the shed to a point beyond that to which the largest particle of 15 unburdened gangue can proceed. With this as a measure of required service of the gun, it is a simple matter to ascertain the degree to which the ore needs to be pulverized and 20 the pressure of air which needs to be maintained in the nozzle or gun.

In dealing with ores which contain several metals in a native or pure state, or substantially such so far as concerns the 30 respective specific gravities of the several metals or metal compounds, it is possible by the described means to secure an approximately clear separation of the several metals upon the floor of the space or hopper, 20. This I have indicated by showing, in dotted lines, several separate troughs or hoppers, 20', in the floor portion, 20. Beginning at the far-end of the shed, these troughs may be taken to represent a series of metals of 40 different specific gravities, such as platinum, gold, lead, silver, etc. However, as a rule, it is sufficient to collect all of the rich or heavy concentrates in the hopper or floor section, 20, leaving to the metallurgist the 45 usual task of refining and separating the same by chemical means, with or without the aid of heat. It will be understood that the great bulk of the pulverized ore, to wit, the gangue proper, is deposited in the large 50 hopper, 18. The discharge of the hopper, 18, may be through the waste conduit or tunnel, whence the gangue is removed to a spoil bank. The low grade or poor concentrate is deposited in the intermediate hopper, 19, from whence it may be taken for 55 direct reduction by the metallurgist; but preferably I discharge the poor concentrate into the return duct, 19', and thence carry it back to the mill, 6, or to a separate mill 60 if desired, to be reground and again projected through the concentrating gun or nozzle, 15, whereby a further separation of the metals from the gangue is secured, with a view to lessening the work of the metallurgist. 65

Obviously a considerable volume of air is discharged into the shed, 4, and while it is desirable to maintain a slight pressure therein, whereby to increase the impeding action of the air upon the projected particles from the gun, there is of course a practical limit which must be observed, both to avoid disruption of the walls of the shed, and a too great back pressure at the mouth of the gun; hence the provision of the 70 valved vent or vents, 21, whereby a substantially constant low pressure condition may be maintained in the shed.

To avoid loss of extremely fine particles of metal, the vents preferably are arranged 80 approximately above the gangue hoppers, beyond which point the heavy particles are sure to be projected. This manner of venting the shed is attended by the advantage of the banking of the air in the closed end 85 of the shed, for the more certain precipitation of the metal particles and heavily loaded pieces of gangue after they pass over the floor sections or hoppers, 18 and 19.

Lest it be thought that this process 90 entails the expenditure of much force in the compression of air, I will explain that an air-gage pressure of considerably less than forty pounds in the gun, 15, accomplishes the projection of the metal particles to distances upward of one hundred feet while the gangue particles are seldom found beyond forty feet, and which therefore is 95 fully adequate for the accomplishment of the separating or concentrating effect here 100 described.

It will be understood that there is a top closure or valve, 10, for each tank, and also a bottom closure or valve, 27, for each tank. When filling a tank from the mill, the 105 valve, 10, is of course open, while the valve, 27, is closed. When the tank, 9, is substantially filled with pulverized ore, the valve, 10, is closed. Thereupon compressed air from the pipe, 17, is admitted to the tank 110 through the pipe, 22, and preferably also to the top of the tank through a branch pipe, 22''. The maximum pressure of the system, say sixty-five pounds absolute pressure, is thus placed upon the material in 115 the tank, 9. Then after closing the discharge valve, 27, of the other tank, I open the like valve 27 of the tank which has been filled and put under pressure; at the same time opening the valve, 23', belonging 120 to the mixing head, 12. Thereupon the pulverized ore under compulsion of pressure in the tank, 9, and aided by gravity and the exit of air from the pipe, 22, flows through the opening between the seat, 25, and the valve, 27. Upon emerging therefrom, the ring or film of pulverized ore receives the added impulsion of the full pressure of air flowing through the converging channel or jet, 26. By this means the burdening of an 125 130

air current with ore is accomplished. The current of mixed air and ore passes swiftly downward through the elbow, 14, and enters the combining tube or conical passage, 35. 5 Due to the shape of this passage, the pressure energy of the stream is in part converted into velocity energy and the particles of ore take on a higher velocity. Entering the communicating pipe, 36, at this velocity, 10 the stream next encounters the second combining tube, 37, wherein the velocity of the particles is again augmented. In consequence, the stream emerges from the tip, 38, at a pressure considerably lower than 15 the initial or starting pressure, but at a high velocity. To be exact, the pressure at the tip, 38, under the conditions of initial velocity developed approximates fifty-eight per cent. of the initial pressure following 20 the law of maximum efflux and has a velocity corresponding to that pressure.

If it were possible to attain a sufficient velocity it might be feasible to project the particles direct from the nozzle tip, 38; dispensing with the head shown thereon, but a stream projected from such a nozzle tip, due to immediate expansion into the atmosphere, sets up detrimental conflicting movements among the particles, robbing some 30 thereof of the true trajectories which should be given them if the best concentrating effects are to be secured. The head, 39, which I have invented, and the pressure of air which I use therein, not only suppress this 35 objectional action, but also operate greatly to increase the linear velocity of the particles suspended in the stream of air. The first essential of this head comprises the secondary nozzle tip and mouth, 45, in the 40 form of a conical passage, the inner end of which is of the same diameter as the tip opening of the nozzle, 38, and the large end of which is outward. The function of this conical passage, whether or not forming a direct, or as shown indirect, continuation of the reversely tapered tip, 38, is to 45 restrict the lateral expansion of the stream of air and thereby necessitate the linear expansion thereof; whereby further velocity is imparted to the particles after leaving the tip, 38. If it were not for the outwardly flared passage, 45, the air would be 50 permitted to expand abruptly on leaving the tip, 38, and the consequence of such uncontrolled expansion would be the deflection of some of the particles from their direct linear paths. By thus limiting the lateral expansion to that simple degree which directly responds to the drop of pressure occasioned by the unrestricted linear expansion, I am able to convert the pressure energy of the stream into velocity energy and motion, which is the force desired for the 55 propulsion of the particles. Thus I secure the highest speeds derivable from the in-

itial or starting pressure at the pumping engine or blower.

For the best functioning of the outwardly enlarged conical passage or mouth, 45, and for the preservation thereof against the 70 abrading action of the particles of ore, I provide means for two other purposes, to wit, means to prevent the lateral expansion or enlargement of the jet as it emerges from the tip, 38, and, second, means to defend the 75 walls of the conical passage, 45, from the impact of the particles of ore which pass through it. These purposes I accomplish through the employment of the air chamber, 40, by the employment of a space or gap, 80 40', between the two parts, 38, and 44, and by admitting air under pressure to the chamber, 40, through the crack, 43, leading from the space, 41. The valve, 17^a, which is included in the pipe branch, 17", is preferably 85 a pressure reducing valve, whereby the maximum pressure in the supply pipe, 17, is reduced in the chamber, 40, and made to equal the static pressure in the stream which emerges from the nozzle, 38. Upon opening or freeing the valve, 17^a, therefor, air is admitted to the chamber, 40, at the stated pressure. This compressed air from the chamber, 40, finds escape in conjunction with 90 and as an envelop for the jet which emerges from the tip, 38. To facilitate the forming of this air-envelop around said jet, and within the passage, 45, I preferably 95 reversely bevel the intake end of said passage, 45, as shown at 45'. Obviously the emerging jet cannot expand within the gap, 40', for the reason that it is encompassed by an 100 atmosphere of the same pressure. Obviously also, as the air from the chamber, 40, finds exit through the passage, 45, the envelop which it forms upon the initial jet is 105 preserved directly upon and against the walls of the conical passage, 45. In this manner, the initial jet is prevented from expanding suddenly; also, is limited substantially to linear expansion within the passage 45; and the walls of said passage are lubricated by the added envelop of air 110 and thus are protected against abrasion by the particles within the jet.

It will now be understood that air composing the jet is allowed to expand substantially down to atmosphere by the time it emerges from the passage, 45, and though it preserves its velocity, it is robbed of its 115 capacity to disperse or laterally disturb the particles which it contains in suspension. It will also now be understood that by means of the compound nozzle here depicted, I 120 secure a very valuable augmentation of the 125 velocity of the particles of ore and what is of great practical value, secure this effect by the expenditure of little force and concurrently protect the nozzle in such manner as to preserve it against rapid destruction. 130

This last is especially important when it is considered that the best effects are secured only when the taper of the nozzle, 45, is determined by an exact mathematical calculation of that lateral expansion of the emerging jet which must be permitted to avoid the building up of a back pressure or the impedance of linear expansion on the one hand; or an excessive lateral expansion and 10 concurrent lateral displacement of particles on the other hand; therefore, it is desirable that the exact predetermined shape shall as long as possible be preserved against an abrading or cut action which would change 15 its shape.

By way of example, drawn to accord with a mountain altitude and an atmospheric pressure of ten and one-half pounds, it may be stated that an initial pressure of sixty-five pounds absolute in the blower pipe, 17, and hence at the openings of the pipes, 22 and 23, affords a pressure closely approximating thirty-eight pounds absolute at the tip, 38; and in such cases the reducing valve, 25 17^a, is adjusted to maintain the same pressure, to wit, thirty-eight pounds absolute in the internal chamber, 40, of the nozzle head. Under these conditions the conduit between the elbow, 14, and the tip, 38, may be reduced to a length of approximately eighteen 30 inches, and yet admit of the attainment of maximum velocity by the particles therein. In practice, I prefer that this dimension shall be increased one or more times as a 35 factor for safety as well as for mechanical convenience. With the equipment shown and at the pressures indicated, the air is expanded substantially to that of the atmosphere on emergence from the nozzle, 45, and 40 to the particles held in suspension therein, there is imparted a substantially uniform velocity of about seven hundred feet per second.

My invention is not limited to the employment of air as the vehicle for carrying and expelling the pulverized material, for it will be evident that other compressed gases may be substituted; and likewise superheated steam may be used with substantially 50 the same results as the gun or nozzle is concerned, but with the disadvantage of a wet concentrating shed due to the condensation of the steam therein. I desire also that it shall be understood that my invention is applicable to materials other than ore.

I claim:

1. An ore concentrating apparatus embodying therein an ore receptacle having a discharge passage therein; a conduit leading from the discharge passage; means for admitting air to the conduit to facilitate the flow of ore therethrough; and means at the terminus of the conduit for increasing the velocity of the ore; said means comprising a chamber in which the conduit termi-

nates, a nozzle leading from the chamber, being spaced from the terminus of said conduit, and having an outwardly flaring passage in axial alinement with the terminus of the conduit, and means for supplying and maintaining an air pressure condition in said chamber substantially equal to the static pressure of the air that discharges thereinto from said conduit.

2. An ore concentrating apparatus embodying therein an ore receptacle having a discharge passage therein; a conduit leading from the discharge passage; and having a converging nozzle passage at its end; means for admitting air to the conduit to facilitate the flow of ore therethrough; and means at the terminus of the conduit for increasing the velocity of the ore; said means comprising a chamber in which the converging conduit passage terminates, a nozzle leading from the chamber, being spaced from the terminus of said conduit, and having an outwardly flaring passage in axial alinement with said converging nozzle passage, and means for supplying and maintaining an air pressure condition in said chamber substantially equal to the static pressure of the air that discharges thereinto from said conduit.

3. An ore concentrating apparatus embodying therein an ore receptacle having a discharge passage therein, a conduit leading from the discharge passage, means for admitting air to the conduit to facilitate the flow of ore therethrough, and means at the terminus of the conduit for increasing the velocity of the ore, said means comprising two longitudinally separated tips containing oppositely tapered nozzle passages in axial alinement and presenting their small openings one to the other, and a chamber surrounding the inner tip, and means for supplying and maintaining an air pressure condition in said chamber substantially equal to the static pressure of the air that discharges thereinto from said conduit.

4. An ore concentrating apparatus embodying therein an ore receptacle having a discharge passage therein, a conduit leading from the discharge passage, means for admitting air to the conduit to facilitate the flow of ore therethrough, and means at the terminus of the conduit for increasing the velocity of the ore, said means comprising two longitudinally separated tips containing oppositely tapered nozzle passages in axial alinement and presenting their small openings one to the other, the large opening of one tip leading to the atmosphere and at the inner end being reversely beveled, and a chamber surrounding the inner tip, and means for supplying and maintaining an air pressure condition in said chamber substantially equal to the static pres-

sure of the air that discharges thereinto from said conduit.

5. The herein described velocity increasing device comprising, in combination, two 5 (outer and inner) longitudinally separated tips containing oppositely tapered nozzle passages in axial alinement and presenting their small openings one to the other, means for supplying a particle-laden aeriform 10 stream to one of said nozzles at a given velocity and static pressure, a chamber surrounding the gap between said tips, means for supplying an aeriform fluid to said chamber at substantially the same static 15 pressure as that of the particle-laden aeriform stream issuing into said gap, whereby lateral dispersion of the stream is prevented and an enveloping and a lubricating stream is formed for discharge through 20 said outer tip with the particle-laden stream.

6. The herein described velocity increasing head, comprising in combination a chamber, a conduit terminating in said 25 chamber, a nozzle spaced from said conduit, having a passage in axial alinement with the terminus thereof, leading from said chamber, and means for supplying and maintaining an air pressure condition in 30 said chamber substantially equal to the static pressure of the air that is to discharge into said chamber from said conduit.

7. The herein described velocity increasing head comprising in combination a chamber, a converging conduit terminating 35

in said chamber, a nozzle spaced from said conduit, having a passage in axial alinement with the terminus thereof leading from said chamber and flaring outwardly, 40 and means for supplying and maintaining an air pressure condition in said chamber substantially equal to the static pressure of the air that is to discharge into said chamber from said conduit. 45

8. The herein described velocity increasing head comprising in combination a chamber, a conduit terminating in said chamber, a nozzle spaced from said conduit having a passage in axial alinement with 50 the terminus thereof leading from said chamber and flaring outwardly, and means for supplying and maintaining an air pressure condition in said chamber substantially equal to the static pressure of the air 55 that is to discharge into said chamber from said conduit.

9. An ore concentrating apparatus embodying therein an ore receptacle having a discharge orifice, a conduit leading from 60 the discharge orifice, a valve positioned in the discharge orifice adapted to regulate the flow of ore therethrough, and means for admitting air to the conduit on the discharge side of said valve, said means including a valve seat and a member adjustable to and from the seat for regulating the flow of air. 65

In testimony whereof I have hereunto set my hand, this 28th day of May, 1919.

FERDINAND GUY GASCHE.
